UNITED STATES PATENT OFFICE.

LAURIE S. MACDONALD AND JOSEPH E. SMALL, OF BROCKTON, MASSACHUSETTS.

BOOT AND SHOE.

Application filed December 22, 1925. Serial No. 76,986.

Our invention relates to boots and shoes and particularly to the construction of the inner soles thereof, the object of the invention being to improve the construction of 5 boots and shoes, and more especially to provide an improved inner sole therefor.

In carrying out our invention the inner sole is made up, essentially, of four sole-shaped members of flexible material cemented one upon the other, the lowermost member consisting of a piece of sole leather to the top side of which is cemented a piece of felt or the like. To the top side of this felt member is cemented a piece of thin waterproof material and on top of this is cemented 15 a sock sole or cover member which may be made from thin leather or other suitable material. All of these parts are of approximately the same size and shape so that the same die may be employed to cut out all of them. The felt member provides a cushion for the foot, while the waterproof member shields the felt from the perspiration of the foot. In one form of our invention a second 20 waterproof member is incorporated in the inner sole between the bottom leather member and the felt to shield the latter from moisture entering the shoe from below. Preferably all of the members are secured 25 together throughout the shank and fore-part by stitches and the heel portion of the bottom leather member is left free and unattached to the heel portion of the next member above it until after the heel is affixed 30 to the shoe. Other features of our invention 35 are hereinafter pointed out.

In the accompanying drawings:

Figure 1 is a plan view, partly broken away, of an inner sole constructed in accordance with our invention.

Figure 2 is a side elevation of the heel portion of the inner sole shown in Fig. 1.

Figure 3 is a central longitudinal section of the inner sole shown in Fig. 1.

Figure 4 is a sectional detail illustrating another feature of our invention.

Figure 5 is a sectional view of the toe portion of a shoe provided with an innersole.

Our improved cushion inner sole comprises, essentially, four sole-shaped pieces of flexible material 1, 2, 3 and 4, all of which are of approximately the same size and shape, except as to thickness. The lowermost piece 1 is the body member and is preferably made from sole leather and may be

provided upon its under side with the usual marginal flap or flaps 5 to which the upper 6, lining 7 and welt 8 of the shoe are stitched, in which case it may be the same in construction as the ordinary inner sole for a welt shoe.

Upon the top side of this body member 1 is a cushion member 2 consisting of a relatively thick piece of felt which, throughout the shank and forepart thereof, is secured by cement, either directly or indirectly, to the top side of the sole leather body member 1, the rear heel portion of said cushion member being left free. On top of this felt cushion member 2 is a member 3 made from any suitable thin waterproof sheet material such as cloth, paper or the like, treated to make it waterproof, and this member is cemented throughout its area—forepart, shank and heel—to the top side of the felt cushion member 2. The top member, or sock sole, 4 is preferably a thin piece of leather such as sheep-skin, or other suitable sheet material, cemented throughout its area to the top side of the waterproof member 3.

After assembling the parts as above described they are further secured together at their edges, but only throughout the shank and fore-part of the sole, by marginal stitches 11 extending through the several members and also cast around their edges, so that the edge portions of the sock sole member 4 and of the body member 1 are drawn together thus inclosing the felt cushion member throughout the shank and fore-part.

Figure 5 is a sectional view of the toe portion of a shoe provided with an innersole constructed in accordance with our invention, and as seen in that figure, the welt 8, upper 6 and lining 7 are stitched, as usual, to the lip 5 upon the bottom side of the body member 1. In this figure 9 is the outersole stitched as usual to the welt 8, and 10 is the usual filling placed between the inner 100 and outer soles.

The heel portion of the felt cushion 2 is left unattached to the body member 1 so that said heel portion, and the heel portions of the waterproof member 3 and sock sole 4, may be bent aside during the operation of affixing the heel to the shoe, after which operation said heel portions are returned to their normal positions and the cushion member is cemented to the body member 1, thus 110 covering the inner ends of the heel nails.

The waterproof member 3 serves to pre-

vent the perspiration of the foot from reaching the felt cushion and, being cemented to the felt member throughout its area, serves also to hold the latter in shape and to prevent it from shifting. In another form of our invention we employ a second sole-shaped waterproof member 3^a which may be made from the same material as the other waterproof member 3, and this second member 3^a is positioned between the felt cushion 2 and the body member 1, being cemented to said felt member throughout its area and to the member 1 throughout only its shank and fore-part. With this form of our invention the felt is protected from moisture both from the foot and from the ground. By thus protecting the felt from all moisture it is kept dry and does not, therefore, mat or lose its resiliency.

20 Besides strongly and positively uniting all of the parts of the inner sole, the stitches 11 also serve to reduce the thickness of the inner sole at its margin throughout its shank and fore-part by drawing the edge portions 25 of the members 1 and 4 together, and to prevent the edges of the several members from loosening and curling up, or the felt from working out from between the members 1 and 3.

30 While we have herein shown our improved inner sole as incorporated in a welt shoe, it will be clear that with slight modification it may be adapted to any other type of shoe made from either leather or rubber.

35 What we claim is:

1. An inner sole comprising a leather sole-shaped body member; a sole shaped top member of soft flexible sheet material; a sole-shaped felt cushion member between the top and body members; a sole-shaped

waterproof member of flexible sheet material between the top and cushion members, and marginal stitches fastening all of said members together throughout their shank and fore-part portions only, all of said members being of the same size and shape and said stitches being cast around the edges thereof and holding the edges of the top member, waterproof member and body member together so as to enclose the felt member. 45 50

2. An inner sole comprising five members all of the same size and shape including a leather sole-shaped body member provided upon its under side with a lip for attachment to the upper and welt of a shoe; a sole-shaped top member of soft flexible sheet material; a sole-shaped felt cushion member between the top and body members; a sole-shaped waterproof member of sheet material between the top and cushion members and cemented throughout its area to both of said members; a second sole-shaped waterproof member of sheet material between the body and cushion members cemented throughout the area of its top side to said cushion member and cemented throughout only the shank and fore-part portions of its bottom side to said body member, and marginal stitches fastening all of said members together but only throughout their shank and fore-part portions, said stitches being cast around the edges of said members and holding the edge portions of the top and body members together so as to inclose the cushion member. 60 65 70 75

In testimony whereof we have affixed our signatures.

LAURIE S. MACDONALD.
JOSEPH E. SMALL.
